UNITED STATES PATENT OFFICE.

JOSEPH SCHWEIZER, OF NEW YORK, N. Y., ASSIGNOR TO THE ANSONIA CLOCK COMPANY, OF ANSONIA, CONNECTICUT.

DESIGN FOR A CLOCK-FRAME.

SPECIFICATION forming part of Design No. 14,955, dated April 8, 1884.

Application filed January 7, 1884. Term of patent 3½ years.

To all whom it may concern:

Be it known that I, JOSEPH SCHWEIZER, a citizen of the United States, residing at New York, in the county and State of New York, have invented and produced a new and original Design for Clock-Frames, of which the following is a specification, reference being had to the accompanying drawing, forming part thereof.

10 The drawing represents a face view of my newly-designed clock-frame formed in the shape of a fan.

The clock-dial A is preferably a small one, and is set in the fan-shaped flange or plate F, as shown. From the point h, where the handle H of the fan joins the body of the frame, are radiating lines r, representing the usual open portion of a fan. Concentric or nearly concentric with the point h are lines l l', the 15 radiating lines r terminating at l. Between the lines l l' are miniature fans f, with their bases on the lower line, l. To the right of the clock-dial A are representations of a flower-

ing plant, P, near which are two or more flying birds, C. Above the clock-dial, and adjoining the upper edge of the frame, is a group of semicircular configurations, D, which serve to complete the design.

I claim—

1. The herein shown and described design, 30 consisting of a clock-frame having the contour of a fan.

2. The design for clock-frames, consisting of a frame having the contour of a fan, ornamented to simulate a fan, substantially as 35 herein shown and described.

3. The design for a clock-frame, which consists of a fan having a handle, H, the radiating lines r, the lines l l', the miniature fans f, the plant P, the flying birds C, and the semicircular configurations D and dial A, as shown and described.

J. SCHWEIZER.
